(57) **CLAIM**

I claim the ornamental design for a pan, as shown and described.

DESCRIPTION

FIG. 1 is a right, front, and top perspective view of the new pan of the present invention;

FIG. 2 is a front view thereof;

FIG. 3 is a top view thereof;

FIG. 4 is a bottom view thereof;

FIG. 5 is a right side view thereof; the left side view is a mirror image thereof; and,

FIG. 6 is a rear view thereof.

1 Claim, 6 Drawing Sheets

RIGHT, FRONT AND TOP PERSPECTIVE VIEW

RIGHT SIDE VIEW; THE LEFT SIDE VIEW IS A MIRROR IMAGE THEREOF
